UNITED STATES PATENT OFFICE.

GEORGE H. BREYMAN, OF TOLEDO, OHIO.

AMALGAMATOR.

SPECIFICATION forming part of Letters Patent No. 707,296, dated August 19, 1902.

Application filed August 12, 1901. Serial No. 71,714. (No model.)

To all whom it may concern:

Be it known that I, GEORGE H. BREYMAN, a citizen of the United States, residing at Toledo, in the county of Lucas and State of Ohio, have invented certain new and useful Improvements in Amalgamators; and I do declare the following to be a full, clear, and exact description of the invention, such as will enable others skilled in the art to which it appertains to make and use the same, reference being had to the accompanying drawings, and to the figures of reference marked thereon, which form a part of this specification.

A familiar difficulty encountered in the use of amalgamating-machines is that the quicksilver when agitated with the gold-bearing material is finely subdivided into minute particles which on being exposed to the air quickly become oxidized, thus producing a "floured" mercury. A very large per cent. of this floured mercury is lost in the tailings, forming a heavy item of expense in the use of the machine.

My invention relates to and its object is to provide means for overcoming the difficulty here indicated by the entire exclusion of air during the operation of amalgamation.

My invention is also designed to provide means for placing the contents of the chamber of the amalgamating-machine under hydraulic pressure during the amalgamating process, thus insuring a more intimate contact and admixture between the pulp and the quicksilver.

My invention also relates to certain details of construction hereinafter described, and pointed out in the claims.

I attain the objects above referred to by means of the devices, mechanism, and arrangement of parts hereinafter described, and shown and illustrated in the accompanying drawings, in which—

Figure 1 is a side elevation of my machine, partly in central longitudinal vertical section, with a portion of the drum hereinafter referred to broken away to show its internal arrangement; Fig. 2, an end view of my machine with a portion of the end of the drum broken away to show the form and relation of the rotary agitators hereinafter referred to, and Fig. 3 is a diagrammatic side elevation of my apparatus.

Like numerals of reference indicate like parts throughout the drawings.

In the drawings, 1 is a cylindrical metal drum closed at both ends by plates 1^a and having circumferential tracks or ways 2, which rest upon suitable rollers 2^a, journaled and mounted upon a stout base or frame 3. The drum is provided with a circumferential rack 4, which is engaged and driven by pinion 5 on driving-shaft 6, this shaft being operatively connected with some suitable source of power. The pinion 5 revolves with but is movable along its shaft and may be thrown into and out of gear with the rack 4.

7 are a series of agitator-rolls disposed at equidistant intervals within the drum and near to its cylindrical wall. These agitators are nearly the length of the interior of the drum 1 and are mounted upon and secured to shafts 7^a, which extend at both ends through stuffing-boxes 8 in the plates 1^a, forming the ends of the drum. These agitators are corrugated or fluted longitudinally. The longitudinal grooves or channels may be varied in transverse section to meet the requirements of the conditions under which the machine is to be worked. In the form which I have illustrated, for example, the corrugations 7^b are serrated, so that the agitators present in transverse section the appearance of a circular saw having large teeth, the points of which are acute angles, the angles at the base of the teeth forming pockets. At 85 one end of the drum the projecting extremities of the shaft 7^a carry pinions 7^c. These pinions are all engaged by a gear-wheel 9, which has a hub 9^a, upon which is secured a sprocket-wheel 10. This sprocket-wheel is 90 driven by chain 11, passing over sprocket-wheel 12 and counter-shaft 13. This shaft carries a sprocket-wheel 14, which is driven by chain 15, running upon a sprocket 16 on the driving-shaft 6. The last-mentioned 95 sprocket-wheel is loose upon the shaft and is thrown into and out of engagement with its shaft by means of a clutch 17, movable longitudinally upon but revoluble with its shaft.

Projecting from the center of one end of the drum is a hollow trunnion 18 and from the other end a hollow trunnion 19. The first-mentioned trunnion forms a support upon which the hub 9^a of the sprockets 9 and

10 is loosely mounted. A feed-pipe 20 leads into the interior of the drum through stuffing-box 21 in the end of the trunnion 18. An outlet-pipe 22 leads from the chamber of the drum through a stuffing-box in the trunnion 19. The horizontal pipe 20 has at its inner end an elbow and terminates in a pipe disposed and adapted to swing in a vertical plane. The pipe 22 in like manner has at its inner end an elbow and terminates in the pipe 22^a, which swings in a vertical plane. The feed-pipe 20 is connected with a tank, where water and pulp are mixed, and with a pump, by means of which water is supplied to the chamber of the drum and by means of which the water may be placed under pressure. (See Fig. 3.) The inlet and outlet pipes are suitably valved. The latter pipe is provided with an upturned U-shaped bend, as shown. The drum is provided with an air-vent 23 and with a manhole, which does not appear in the drawings.

The operation of my device is as follows: The drum is provided with a charge of mercury, which partly covers the lower agitators. Pulp mixed with water is fed into the drum through pipe 20, the inner end of which, 20^a, is turned toward the bottom of the drum. The pipe 20 is secured against rotation by means of a stout set-nut 20^b at the union between the pipe 20 and the pipe leading from the pulp-tank. The swinging pipe at the opposite end of the drum is in like manner secured by a similar nut 22^b. A charge of pulp is admitted through the pipe 20, and all valves being closed and the water-supply pump being put in motion the chamber of the drum is now filled with water and hydraulic pressure is applied to the contents of the drum. Power is applied to the shaft 6. The drum through the rack and pinion 4 5 is now caused to revolve, and the agitators are set in motion through the pinions on the ends of the agitator-shafts and the train of sprocket-gearing 9, 10, 11, 12, 13, 14, 15, and 16. As the drum turns slowly on its supports each of the agitators is turned on its shaft and the contents of the drum are stirred and thoroughly mixed. The longitudinal channels or grooves upon the agitators catch the pulp and carry it down into and through the mercury, thus after a few rotations of the drum insuring the contact of the mercury with every part of the charge of pulp. Before commencing the rotation of the drum the pipe ends 20^a and 22^a should be turned upwardly, for the reason that if the machinery were started while these pipe ends were embedded in the pulp they would be broken off. Under some circumstances and with some kinds of auriferous material the operation may be continuous and the pulp may be fed down through the pipe 20 close to the bottom of the drum, while the upturned end of the pipe 22^a will permit the escape of the excess of water and the tailings.

It will sometimes be found desirable to ro-

tate the drum without revolving the agitators. In such case, by means of the clutch 17, the train of gearing which revolves the agitators 70 may be thrown out of gear. In like manner the drum may be allowed to stand motionless by moving the pinion 5 along its shaft out of gear with the rack 4. Thus both of the driving mechanisms may at all times be operated, 75 either in conjunction or independently of each other.

To those skilled in the art modifications of the mechanical means by which rotation of the drum and of the agitators is secured 80 and of the means for feeding and withdrawing the pulp into and from the drum and of placing the contents of the drum under hydraulic pressure will suggest themselves, and I do not, therefore, limit my invention to the 85 exact form of apparatus here shown.

Having described my invention, what I claim, and desire to secure by Letters Patent, is—

1. In an amalgamating-machine, the combination of a rotary cylinder and suitable trunnions therefor, inlet and outlet pipes leading through said trunnions and having bent ends within the cylinder adapted to be turned either upward or downward, a series of agitators 90 within the cylinder, means for hermetically sealing said cylinder, operating means for the cylinder and agitators, separate driving connections between the cylinder and agitators and the operating means, and means for throwing 95 either driving connections out of operation.

2. In an amalgamating-machine, the combination of a rotatable cylinder having an axial inlet and axial outlet, means for hermetically sealing said cylinder, means for placing the contents of the cylinder under hydraulic pressure, agitators disposed within the cylinder, operating means for the cylinder and agitators, separate driving connections 105 between the cylinder and agitators and the operating means, and means for throwing either driving connections into or out of engagement with the operating means whereby both the cylinder and agitators may be axially rotated 110 in unison or the one held stationary while the other is rotated.

3. In an amalgamating-machine, the combination of a cylinder having suitable trunnions, an inlet-pipe leading into the cylinder 120 through one of said trunnions, an outlet-pipe leading from the cylinder through the other of said trunnions, each of said pipes having the ends within the cylinder bent and adapted to be turned upward or downward within 125 the cylinder, the outlet-pipe having an upturned U-shaped bend outside of said cylinder, a series of agitators within said cylinder, operating means for the cylinder and agitators, separate driving connections between 130 the cylinder and agitators and the operating means, and means for throwing either driving connections into or out of engagement with the operating means.

4. In an amalgamating-machine, the combination of a cylinder having an axial inlet and an axial outlet, means for hermetically sealing said cylinder, a series of agitators mounted for rotation within said cylinder, means for rotating said cylinder, a clutch for connecting and disconnecting the cylinder with its operating means, independent mechanism for imparting axial rotation to said agitators, and a clutch for connecting and disconnecting the agitators to their operative mechanism whereby the cylinder and agitators may be given axial rotation or held at rest the one independent of the other.
- In testimony whereof I affix my signature **15** in presence of two witnesses.
- GEORGE H. BREYMAN.
